US00D721992S

(12) **United States Design Patent**
Takei et al.

(10) **Patent No.:** US D721,992 S
(45) **Date of Patent:** ** Feb. 3, 2015

(54) **FRONT BUMPER FOR AN AUTOMOBILE**

(71) Applicants: **Tatsuya Takei**, Toyota (JP); **Yuki Isogai**, Nissin (JP)

(72) Inventors: **Tatsuya Takei**, Toyota (JP); **Yuki Isogai**, Nissin (JP)

(73) Assignee: **Toyota Jidosha Kabushiki Kaisha**, Toyota-shi, Aichi-ken (JP)

(**) Term: **14 Years**

(21) Appl. No.: **29/486,283**

(22) Filed: **Mar. 27, 2014**
